UNITED STATES PATENT OFFICE.

SAMUEL H. GARVER, OF DECATUR, ILLINOIS.

PORTABLE STRAW-STACKER.

SPECIFICATION forming part of Letters Patent No. 288,224, dated November 13, 1883.

Application filed January 23, 1883. (No model.)

To all whom it may concern.

Be it known that I, SAMUEL H. GARVER, residing near Decatur, in the county of Macon and State of Illinois, have invented certain new and useful Improvements in Portable Straw-Stackers, of which the following is a full, clear, and exact description, such as will enable any one skilled in the art to which it relates to construct the same.

10 My invention relates to straw-stackers; and it consists in a portable frame provided with a pivoting straw-elevator and a revolving brace-adjuster, by means of which straw may be carried from the thrashing-machine at various angles, both vertical and lateral, said elevator and brace-adjuster having peculiarities of construction and operation that, with the general construction, will be hereinafter fully set forth.

20 In the drawings accompanying and forming a part of this specification, Figure 1 is a side elevation of a stacker in which my invention is embodied. Fig. 2 is an end view of the pivoting straw-carrier supporter, showing the device used to convert oscillating motion from the thrashing-machine into rotary motion in the stacker. Fig. 3 is a plan of the brace-adjusting device. Fig. 4 shows the frame that supports the straw-carrier when the machine 25 is made portable; and Fig. 5 is an elevation of an end of the brace-adjusting frame, showing the rack and pinion used to assist in effecting said adjustment.

30 *a* is a frame that carries belt *b*. *c* and *d* are belt-tighteners. *ef* is a cord and weight which, supported by pulley *g*, operates belt-tightener *d*. *h* and *i* are belts. *k* is a brace hinged to the belt-frame *a* at its upper end and attached to a shaft that is provided with pinions *p*, which 35 work in rack *y*. *m* is the rotating support, in which frame *a* pivots. *n n* are side pieces of the revolving brace-adjuster, each provided with a rack, *y*, and a slot, *o*, in which the pin-

ions and their shaft operate. *l* is a rod which connects crank *x* with the thrashing-machine. 45 *w* is a pulley for belt *i*. *t* is the bed or portable frame provided with extension *v*, on which *m* rests. *z* is a revolving drum, which supports side pieces, *n n*, and which is provided with a rim that works in guides *q q*. *s* is a 50 detachable frame that is used to support the belt-carrier *a* when the same is not in use, and *r* are loops which secure frame *s*. *q'* is a lever which is used to operate the pinions in their rack.

55 Drum *z* may be provided with cogs, and a crank-gear attached to frame *t* to revolve said drum, or levers of various kinds may be used for the same purpose.

The machine, as shown in Fig. 1, is in condition for work. By turning lever *q'*, the pinions may be carried to the opposite end of the rack, when the frame *a* will rest on support *s*. A partial revolution of the drum will change the lateral position of the straw-discharge. 65 By changing the position of the pinions in the rack the vertical position of the straw-discharge may be varied. Belts *h* and *i* run over pulleys on a shaft in swinging frame or tightener *d*. *i* conveys the motion to the shaft from *w*, and *h* carries it onto the roller by which belt *b* is operated.

Having thus described a device in which the principles of my invention are embodied, I claim—

1. The combination, with portable frame *t*, of drum *z*, support *m*, carrier *a*, braces *k*, and frame *n*, as and for the purpose set forth.
2. The combination, with frame *t*, support *m*, drum *z*, braces *k*, and frame *n*, of rack *y* 80 and pinion *p*, as and for the purpose set forth.

SAMUEL H. GARVER.
